UNITED STATES PATENT OFFICE.

WILLIAM JOSEPH RIDER, OF HORLEY, ENGLAND.

SEAT.

1,391,275.

Specification of Letters Patent. Patented Sept. 20, 1921.

Application filed January 3, 1921. Serial No. 434,702.

To all whom it may concern:

Be it known that I, WILLIAM JOSEPH RIDER, a subject of the King of Great Britain and Ireland, residing at Gardenside, 5 Oakwood Road, Horley, in the county of Sussex, England, have invented new and useful Improvements in Seats, of which the following is a specification.

The invention relates to seats, and consists of improvements which are particularly intended for use with the seats used in cinemas, theaters and the like, though they may be also applied to other seats and chairs.

15 The seats used in cinemas, theaters and the like are arranged in rows, and the distance between each row is made as narrow as possible in order that the seating accommodation shall be as large as possible.

20 Owing to the narrow width of the space between successive rows of seats, when a person has to pass to an unoccupied seat other than a seat at one of the ends of a row of seats it is necessary for one or more of

25 the persons already seated to rise in order to allow the newcomer to reach his seat. The same holds good when a person, under the same circumstances, leaves his seat. The necessity of said person or persons having 30 to rise, which is also necessary when tip-up seats are used, is a great inconvenience to the occupants of the seats in rear of the row in question, as their view of the screen, stage or platform is obstructed for some considerable time.

With a view to obviating the above referred to inconvenience I devised a construction of seat which renders it unnecessary for the occupants of cinema and like seats 40 to rise when persons wish to pass, as aforesaid, to unoccupied seats or to leave their seats. With this construction of seat, see the specification of my application for Letters Patent of the United States, Serial No. 410,184, dated September 14th, 1920, all that 45 the occupant of a seat has to do to allow a person to pass to an unoccupied seat or to leave his seat is to either swing his legs to the right or left or while the seat is in its 50 normal position to merely move it backward.

The present invention consists of an improved construction of seat in which the mechanism employed is not only of simpler nature and cheaper to manufacture than the 55 mechanism described in said specification

but will also allow the seat to be moved backward at any time.

The invention is illustrated by the accompanying drawings.

Figure 1 is a front view and Fig. 2 is a 60 plan illustrating the application of the invention to two seats, such as those used in cinema halls. Fig. 3 is a side view of said seats. Fig. 4 is a plan illustrating the preferred construction of the improved seat. 65 Fig. 5 is a part side elevation and part transverse section of the same construction of seat. Fig. 6 is a plan of the relatively fixed plate of the seat. Figs. 7 and 8 are views, corresponding to Figs. 4 and 5, illustrating a modified construction of the improved seat. Fig. 9 is a view of the relatively movable plate of the same construction of seat seen from below, and Fig. 10 is a plan of the relatively fixed plate of the 75 seat.

In all of the figures the same parts when of identical construction are indicated by the same reference numerals.

Referring first to the construction of seat 80 shown in Figs. 1 to 6, 1 is a relatively fixed board or plate, hereinafter referred to as the fixed plate of the seat, which is either secured to the frames 2 of the seat, or, in the case of a tip-up seat, is pivotally supported 85 by said frames. 3 is a relatively movable board or plate, hereinafter called the movable plate of the seat, and 4 is a slot formed in the plate 3. 5 is the seat proper secured to the plate 3. 6 is a sector-shaped plate, 90 hereinafter referred to as the sector, which is secured to the fixed plate 1 and extends through one half of a circle. 7 is a groove formed in the curved periphery of the sector 6. 8 and 9 are two lengths of wire rope or 95 the like which are secured at their ends to the fixed plate 1 and to the movable plate 3 in such positions as to coöperate with the groove 7 of the sector 6. 10 is a bolt that serves not only as a pivot for the movable 100 plate 3 but also as a means for connecting the two plates to one another. The bolt 10, the axis of which is coincident with the center from which is struck the sector 6, passes through a hole 11 in the fixed plate 1 and 105 through the slot 4 formed in the movable plate 3 and is secured in position by means of a nut 12 and washer 13. 14 is a coiled spring that is housed in the slot 4 and bears at its outer end against the front end of said 110

slot and at its inner end against a block 15 contacting with the stem of the bolt 10. The block 15 is preferably made of the shape shown, see particularly Fig. 4, that is to say 5 is provided with a stem 15', that enters into the spring 14, and with a head 15" the front face of which is curved to correspond to the bolt 10. 16 is a plate screwed to the upper face of the movable plate 3 for the purpose 10 of retaining the spring 14 in position in the slot 4.

The mechanism described above acts as follows:

If the occupant of a seat has to move to 15 allow a person to pass in front of him he swings his legs toward his right or left side. If he swings his legs toward his right side the length of wire rope or the like 9 on the left side of his seat will wind itself on to the 20 left hand half of the sector 6, while the length of wire rope or the like 8 on the right side of his seat will become disengaged from the right hand half of the sector 6. As a 25 result of the movement given to his legs by the occupant of the seat the movable plate 3, and therefore the seat proper 5, will be moved backward and also to one side of its 30 normal position. When said person has passed the occupant of the seat the occupant 35 swings his legs back into their original position, and returns the movable plate 3 to its original position, a movement which is assisted by the action of the spring 14. If the occupant of the seat swings his legs toward his left side similar actions will take place, the length of wire rope or the like 8 on the 40 right side of his seat winding itself on to the right hand half of the sector 6 and the length of wire rope or the like 9 on the left side of his seat becoming disengaged from the left 45 hand half of the sector 6. The occupant of the seat instead of swinging his legs to either the right or the left may force the movable plate 3 backward. This backward movement 50 of the plate 3 may be effected either when the seat is in its normal position or when the seat has been partly rotated on the bolt 10. The seat however is preferably merely swung to one side, as this allows a passage-way of greater width.

Referring now to the modified construction of seat, illustrated by Figs. 7 to 10 of the accompanying drawings, it will be seen that the slot 4 which allows a seat to be 55 simultaneously swung on the bolt 10 and moved backward, or merely moved backward, is formed in the relatively fixed plate 1 of the seat, and the sector, 6, of the previously described construction of seat is replaced by a disk 17, which is secured to the 60 movable plate 3 and is provided with a peripheral groove 18, while the two lengths of wire rope or the like, 8 and 9, are replaced by a single length 19 of wire rope or the like 65 of loop shape, which is anchored at its ends

to the fixed plate 1 and is secured at its center to said disk. Otherwise the parts of the modified construction of the improved seat are the same as those shown in Figs. 1 to 6 and are indicated by the same reference numerals. 70

The parts of the modified construction of seat coöperate as follows:

If the occupant of a seat swings his legs to one or the other side the movable plate 3 75 will simultaneously turn on the bolt 10 and move backward, the bolt 10 traveling in the slot 4 and compressing the spring 14, while the half of the disk 17 on the opposite side of the seat will become engaged to a greater 80 extent with the half of the wire rope or the like 19 on the same side of the seat, and the other half of said wire rope or the like, becoming slack, will be wholly or partly disengaged from the groove 18 formed in the 85 periphery of the disk 17. As in the case of the first described construction of seat, the occupant of a seat fitted with the modified mechanism can move the seat backward either when the seat is in its normal position 90 or when it has been partly swung to one side of said position.

The grooved disk 17 of the last described construction of seat may be replaced by a 95 grooved sector extending through the necessary part of a circle.

What I have invented and desire to secure by Letters Patent of the United States is as follows:

1. A seat comprising a relatively fixed 100 plate, a relatively movable plate carrying the seat proper and operatively connected to said relatively fixed plate by a bolt and slot, mechanism intermediate between said relatively fixed and movable plates consisting of wire rope and of a peripherally grooved plate coöoperating with said wire rope and having its axis coincident with the axis of said bolt, and a spring for returning said movable plate to its normal position when 105 displaced therefrom, substantially as described.

2. A seat consisting of a relatively fixed 110 plate, a relatively movable plate carrying the seat proper, mounted on said relatively fixed plate by means of a bolt, and formed with a centrally disposed slot for said bolt, a sector secured to the upper face of said fixed plate and formed with a peripheral groove, 115 lengths of wire rope secured to said movable and fixed plates in positions to coöperate with said sector, and a coiled spring interposed between the front end of the slot formed in said movable plate and the stem of the bolt by which said plates are pivotally 120 connected to one another, substantially as described.

3. A seat consisting of a relatively fixed 125 plate formed with a centrally disposed slot, a relatively movable plate mounted on said 130

fixed plate by means of a bolt passing through the slot formed in said fixed plate, a disk secured to the lower face of said movable plate and formed with a peripheral groove, a loop-shaped length of wire rope anchored at its ends to said fixed plate and secured at its center to the periphery of said disk, and a coiled spring interposed between the rear of the slot formed in said fixed plate and the stem of the bolt by which the two ¹⁰ plates are pivotally connected to one another, substantially as described.

In testimony whereof I have signed my name to this specification.

WILLIAM JOSEPH RIDER.
